UNITED STATES PATENT OFFICE

RAYMOND E. BROWN, OF PITTSBURGH, PENNSYLVANIA, ASSIGNOR TO HEYL & PATTERSON, INC., OF PITTSBURGH, PENNSYLVANIA, A CORPORATION OF PENNSYLVANIA

CAR DUMPING

Application filed March 20, 1928. Serial No. 263,023.

This invention relates to car dumpers and particularly to a dumper adapted to automatically clamp the car in position for dumping, and to release the same after it has been dumped.

There are several difficulties to be overcome in constructing a practical car dumper, one of these arising from the fact that the car clamps, instead of engaging the car sides, may bear against heaped up coal in the car. The clamps must, therefore, be capable of independent movement so as to insure that the car will be properly clamped. In a car dumper of the tilting type, a heavy load is thrown on the clamps when the car is tilted, and a strong locking means for the clamps must be provided.

It is not satisfactory to simply lock the clamps in position, as by a rigid bolt and ratchet arrangement or the like, because of the fact that when the loaded car is moved on to the dumper, its springs are under compression and the body is relatively low due to the weight of the coal. When the car is empty the springs are not under such high compression and the car body stands relatively further away from the rails. The springs tend to move the car body from its low position to its high position during dumping, and if the clamps are not yieldable the car springs throw a heavy load on them. It will be seen that when the dumper has been returned to such position that the car is again level, the clamps, if non-yielding, will be subjected to an upward thrust by the car springs equal in amount to the weight of the coal originally contained in the car.

I overcome this difficulty by providing a locking device having a limited degree of movement. The clamps are capable of moving outwardly after they have been set, and therefore they will accommodate themselves to the movement of the car body away from the trucks. The car dumper is preferably made with a frame having a platen thereon, this platen having tracks which support the car. When the car dumper is tilted the platen moves sidewise and controls cable connections which permit the clamps to move into engagement with the car. This sidewise

movement of the platen is limited by the side of the car coming into engagement with bumpers or stops on the frame. These bumpers are preferably made movable relative to the frame so that when the frame is sufficiently tilted they will slide outwardly and away from the platen with the car body. As above stated, the clamps are provided with a limited degree of movement, and when the car body slides outwardly the clamps move with it until they reach the end of their travel.

While the car body tends to move away from the platen, and to leave the trucks in fixed position relative thereto, I preferably so form the platen that it tends to follow the trucks in case they move outwardly with the car body. This prevents derailing of the car during dumping. I preferably employ springs or other balance means for the platen, so arranged that when the dumper is in its normal position the downward force, due to the weight of the platen, is slightly in excess of the force exerted by the balance means. As the platen is tilted, the component of gravitational force along the line of force of the balance means becomes gradually less so that the balancing force is sufficient to cause the platen to move outwardly and follow the car, if necessary. In addition to this, the balance means is preferably so arranged that its force increases on sidewise movement of the platen.

In the accompanying drawings, illustrating the present preferred embodiment of my invention,

Figure 1 is a top plan view of a tilting car dumper, partly broken away,

Figure 2 is a side elevation thereof,

Figure 3 is an end view to enlarged scale,

Figure 4 is a transverse section taken on the line IV—IV of Figure 1,

Figure 5 is a detail view showing the locking device for the clamps,

Figure 6 is a side elevation, partly broken away, of one of the stops or bumpers for the car, and

Figure 7 is a diagrammatic view illustrating the clamp lowering arrangement.

The car dumper shown in the drawings comprises a frame having end rings 2 con-

nected by longitudinal girders 3, these longitudinal girders carrying normally horizontal beams 4, and normally vertical members 5. The vertical members 5 support a spill plate 6, and the horizontal beams 4 are provided with rails 7 on which a platen 8 is mounted. The platen 8 has wheels 9 running on the tracks 7 so that the platen may move toward or away from the spill plate 6. The 10 platen carries running rails 10 and guard rails 11 for accommodating a car to be dumped.

The end rings 2 have openings 12 therein through which a car may pass to or from the platen 8. The end rings have rails 13 engaged by flanged wheels 14 on a sub-frame 15 by which the tilting portions of the dumper are carried. The end rings are also provided with ring gears 16, which ring gears are engaged by gears 17 journaled in the sub-frame 15. The gears 17 mesh with pinions 18 on a longitudinally extending shaft 19. The shaft is driven by a motor 20 through worm gearing, indicated at 21, whereby the frame and platen, with a car thereon, may be rotated in either direction, as desired.

The frame is rotated clockwise, as viewed in Figures 2 and 3, in order to dump the contents of a car. During this clockwise movement the tracks 7 of the platen are inclined so that the platen tends to travel toward the spill plate. The sidewise movement of the platen on the rails 7 is controlled by horns 22 which are secured to the foundation and extend inwardly far enough to engage lever arms 22a carried by the platen adjacent each of its ends and pivotally connected thereto at 22b. When the car dumper is in its normal position, as shown in Figures 3 and 4, the platen is engaged at one side by stops 23 formed on the main frame, and the lever arms are engaged by the horns 22. In this position the arms lie against the platen, so that its position is definitely determined and it is in proper alignment with the tracks T by which the cars are supplied to and taken away from the dumper.

When the car dumper is rotated clockwise, the tracks 7 are tilted and the platen, due to its own weight and the weight of the car carried thereby, tends to run down-hill. This movement is resisted by the horns 22, but since the frame continues to rotate clockwise, as viewed in Figures 3 and 4, relative movement between the platen 8 and the beams 4 takes place until the side of the car comes into engagement with stops or bumpers 24. The bumpers 24 lie against the spill plate 6 and are slidably between angles 25 secured to the spill plate, as hereinafter more fully described.

The sidewise movement of the platen toward the spill plate is effective for lowering car clamps 26 into engagement with the car. 65 Each car clamp consists of a slide 27 having

a projecting arm 28 on which the clamp proper 29 is pivotally mounted. The slide 27 works in guides 30 on the spill plate 6. Each slide 27 has a lowering cable dead-ended thereon at 31. The cable extends upwardly, 70 as indicated at 32, and over a sheave 33 secured to the main frame. Each sheave 33 extends through an opening formed in the spill plate and serves to carry the cable to the rear of the spill plate. The cable passes over the sheave 33 and downwardly around a sheave 34. From the sheave 34 the cable extends to a sheave 35 adjacent the end of the dumper, and then passes downwardly and over a sheave 36. The cable is then reeved around sheaves 37 on the arms 22a, and sheaves 38 on the frame, the end of the cable being secured to a tension spring 39, the upper end of the tension spring being fastened to the frame. When the platen 8 moves toward the spill plate, the sheaves 37 are correspondingly moved toward the sheaves 38, thus permitting the clamps to drop by their own weight. The reeving of the cable between the sheaves 37 and 38 is effective for multiplying the movement so that the total possible drop of the clamps is a multiple of the total sidewise movement of the platen.

Continued tilting of the frame after the car body comes into engagement with the bumpers 24 permits the arms 22a to swing about their pivots 22b toward the spill plate 6, thus providing ample movement for the clamps. The tension springs take up all slackness in the cables and prevent them from running off the sheaves.

The slide 27 of each clamp has ratchet teeth 40 formed on its rear face, and openings 41 are provided in the spill plate 6. A dog 42 extends through each opening so as to engage the teeth. Each dog is provided with an elongated opening 43 through which a pin 44, fastened to the frame, passes. Each dog has an arm 45, and a link 46 connects the arm 45 with a pendulum 47. The pendulum 47 is pivoted to the frame 48 and when the car dumper is level, the weight of the pendulum is sufficient to hold the dog 42 out of engagement with the ratchet teeth 40.

Figure 5 shows the position of the several parts of the ratchet and dog mechanism when the car dumper is level, and it will be noted that the pendulum lies at a material angle to the vertical. The spill plate acts as a stop, bearing against the link 46 so as to prevent the pendulum 47 from swinging to the vertical position. The movement of the dog and pendulum is not necessarily limited in this manner, but it is desirable in that movement of the parts is reduced to a minimum.

As the car dumper is tilted, the pendulum and the dog maintain the position shown in Figure 5 until the car dumper assumes such angularity that the pendulum is hanging vertically from its pivot 48. This gives the

platens ample opportunity to move sidewise and permit the clamps to lower. Continued tilting of the car dumper causes the pendulum to swing away from the spill plate and move the dog 42 into engagement with whichever ratchet tooth is presented, thus locking the clamp in position.

As the car is tilted, the force on the car springs is reduced by reason of the fact that the component of the gravitational force is progressively lowered. This causes the springs to expand and to urge the car body away from the platen. If the dogs 42 were arranged so as to lock the clamps non-yieldingly, the force thrown on the dogs would be so great as to practically preclude their unlocking after the car had been emptied and returned to its normal position. However, the provision of the slots 43 makes it possible for the dogs to slide relative to the pins 44, thus permitting the clamps to move outwardly to a limited degree and compensate for the movement of the car body away from the platen. During this movement the stops, or bumpers, 24 slide along the spill plate 6. These stops are provided with cross pins 49 working in slots 50 in the angles 25.

The amount of movement permitted by the slots 43 is sufficient to compensate for the difference in the position of the car body relative to the rails when in loaded and in unloaded condition, but for several reasons it is desirable to insure that the platen will be capable of "following up" the movement of the car and thus insure against derailing. For instance, the amount of total movement of the body of a particular car relative to its trucks might be considerably less than that figured on in designing the car dumper, and therefore the trucks would tend to move away from the platen when the dumper was in extreme dumping position. The platen is therefore provided with balance means which are effective for lifting it away from its tracks 7 and keeping it in constant engagement with the wheels of the car being dumped.

The balancing arrangement is shown in detail in Figure 4. It comprises a pair of parallel arms 51 at each end of the platen, these arms being pivoted to the platen at 52. The arms extend through trunnion blocks 53 and are provided with heads 54 which limit the outward movement of the platen and prevent its falling out of place in the event that no car is on the dumper when it is tilted.

Compression springs 55 are placed around the arms 51. These springs bear at their lower ends on the trunnion blocks 53 and at their upper ends against shoulders formed on the arms. They are placed under an initial compression so that when the platen is on its tracks 7 and in the position shown in Figure 4, the upward force exerted by the springs is slightly less than the weight of the platen.

As shown in Figure 4, the arms are in-

clined away from the spill plate so that as the platen moves toward the spill plate the arms 51 assume a more nearly perpendicular position relative to the platen, thereby further compressing the springs and increasing their power.

When the dumper is in tilted position the weight component of the platen exerted along the axis of the springs is very small, and therefore the springs have sufficient power to urge the platen outwardly and keep its rails in engagement with the wheels of a car on the dumper.

After the car has been dumped, the frame is rotated in a counter-clockwise direction, as viewed in Figures 3 and 4. During such movement each pendulum 47 swings back to its normal position and withdraws its dog 42 from engagement with the clamp ratchets 40. Continued counter-clockwise movement brings the arms 22 into engagement with the horns 22 and the clamps 29 are thus raised away from the car body. When the arms have swung a sufficient distance to lie against the side of the platen, the platen itself, with the car thereon, is moved sidewise relative to the frame and away from the spill plate 6, so that when the return movement is completed the platen, with the empty car thereon, is in alignment with the tracks T, ready for the car to be moved away.

I have illustrated and described the present preferred form of my invention, but it will be understood that it is not limited to this form alone, but may be otherwise embodied within the scope of the following claims:

1. Claim:

1. A car dumper comprising a frame, a platen mounted thereon, a clamp adapted to engage a car on the platen, the platen being movable toward the clamp, and means urging the platen toward the clamp.

2. A car dumper comprising a frame, a platen mounted thereon, a clamp adapted to engage a car on the platen, the platen being movable toward the clamp, and spring balance means for the platen, said balance means urging the platen toward the clamp.

3. A car dumper comprising a tilting frame, a platen mounted thereon, a clamp, means for limiting sidewise movement of a car on the platen, and means effective on tilting movement of the frame and after the sidewise movement of the platen has terminated for moving the platen toward the clamp.

4. A car dumper comprising a tilting frame, a platen carried by the frame and movable relative thereto upon tilting of the frame, and balance means for the platen, the balance means being so arranged as to urge the platen toward the car body and being adapted to increase in effectiveness when the frame is tilted.

5. A car dumper comprising a platen hav-

ing car rails thereon, a clamp and a locking device for the clamp, the locking device having a limited degree of movement, and the platen being movable toward the clamp in such manner as to maintain engagement of the rails with the wheels of a car on the platen as said gear moves in the amount permitted by the clamp.

6. A car dumper comprising a frame, a platen mounted thereon and having car rails, a clamp adapted to engage a car on the platen, the platen being movable toward the clamp and the clamp being also movable to a limited degree after clamping in the direction of movement of the platen, and means urging the platen toward the clamp so as to maintain engagement of the rails with the wheels of a car on a platen as said car moves in the amount permitted by the clamp.

20 7. A car dumper comprising a tilting frame, a platen mounted thereon, side supports for limiting sidewise movement of a car on the platen, and a clamp for engaging a car on the platen, the clamp having a limited degree of movement and the side supports being so arranged and constructed that a car in engagement thereon may move relatively easily with respect to the frame, the platen being movable in the same direction as the clamp and after sidewise movement thereof has terminated.

35 8. A car dumper comprising a tilting frame, a platen mounted thereon, side supports for limiting sidewise movement of a car on the platen, a clamp for engaging a car on the platen, the clamp having a limited degree of movement and the side supports being so arranged and constructed that a car in engagement thereon may move relatively easily with respect to the frame, the platen being movable in the same direction as the clamp and after sidewise movement thereof has terminated, and means for urging the platen toward said clamp.

40 9. A car dumper comprising a tilting frame, a platen movable sidewise in the frame, the platen running on tracks, and means urging the platen away from the tracks.

45 10. A car dumper comprising a tilting frame, a platen movable sidewise in the frame, the platen running on tracks, and spring means urging the platen away from the tracks.

55 11. A car dumper comprising a tilting frame, a platen movable sidewise in the frame, the platen running on tracks, and spring means urging the platen away from the tracks, said springs being of such power as to exert a force which is less than the weight of the platen.

60 12. A car dumper comprising a tilting frame, a platen thereon, means for limiting sidewise movement of a car on the platen, a clamp for supporting the car when the frame

is tilted, and means urging the platen toward the clamp.

In testimony whereof I have hereunto set my hand.

RAYMOND E. BROWN.
